[57] CLAIM

The ornamental design for a modular wrought iron grid, as shown and described.

DESCRIPTION

FIG. 1 is a perspective view of a modular wrought iron grid showing my new design;

FIG. 2 is a front elevational view with the rear side being a mirror image thereof;

FIG. 3 is a left side elevational view thereof;

FIG. 4 is a right side elevational view thereof;

FIG. 5 is a top view thereof; and,

FIG. 6 is a bottom view thereof.

The broken lines in each of the Figures are intended to indicate indefinite length.
